DEVICE ON FOLDING MACHINES

Adolf Stampfli, Aarau, Switzerland

Application October 3, 1933, Serial No. 691,971
In Switzerland July 13, 1933

2 Claims. (Cl. 12—55)

This invention relates to a device on a known folding machine, which renders it possible to paste a reinforcing tape between the parts of the folded seam in a single operation with the folding of the seam.

An embodiment of the invention is illustrated by way of example in the accompanying drawing in which

Fig. 1 shows in perspective the device on a folding machine,

Fig. 2 shows the guide bar in front elevation,

Fig. 3 is a front elevation of the folding foot of the folding machine with the tape feeding eye,

Fig. 4 is a side elevation of Fig. 3,

Fig. 5 shows the paste holder in vertical section,

Fig. 6 shows a portion of a folded seam with reinforcing tape stuck between the parts,

Fig. 7 is a cross section through the seam shown in Fig. 6.

20 A flat lever 4, bent at right angles and carrying a guide eye 3, is pivotally mounted on a folding foot 1 of a folding machine 2 reciprocatable in known manner. The lever 4 is provided with a projection 5, which engages in a corresponding notch 6 in the foot 1 so that the lever is arrested in operative and inoperative position. A guide bar 9 provided with eyes 8 is fixed by means of screws on the machine head 7 above the folding foot and serves for guiding the reinforcing tape.

30 A stand 10 is mounted on the machine table T. An upper carrier 11, adjustable in height on this stand, carries a guide pulley 12. The reinforcing tape 15 is wound on a rotary drum 14 on a lower carrier 13 adjustable on the stand 10. A paste

35 container 16 is arranged under the table T and has in its cover two narrow apertures 17 and 18 for guiding into and out of the container the reinforcing tape 15 to be steeped in paste. Two strippers 19 made of felt are fixed on the inner side of the cover adjacent the outlet aperture 18 and remove any excess paste from the tape. A bracket 21 on the inner side of the container cover dips into the paste 20 and carries on its lower end a guide pulley 22.

45 With the aid of the device described the reinforcing tape 15 is placed between the parts 23 and 24 of the seam whilst this seam is being folded on the folding machine. Merely the seam

is folded over in known manner by the folding machine. During the folding of the seam, the reinforcing tape 15, as shown in Fig. 3, is fed between the parts 23 and 24 by means of the guide eye 3. During this operation the tape 15 5 unwinds from the drum 14, passes through the paste container 16, travels over the guide pulley 12 and is introduced into the continually forming seam 23, 24 by means of the guide bar 9 and guide eye 3 and united by the paste to form 10 a resistant seam as shown in Fig. 7. The tape 15 may be of such width, that it lies entirely within the seam formed by the part 24. The device according to the invention permits the folding of leather pieces having irregular, for example 15 curved edges.

I claim:—

1. A device on a folding machine, comprising in combination with the machine table and machine head and the folding foot, a stand on said table, 20 a carrier on said stand, a roll mounted on said carrier and adapted to receive a supply of reinforcing tape, a paste container below said table adapted to coat with paste the tape running from said carrier, a pulley mounted on said stand 25 adapted to guide the pasted tape leaving said container, a guide bar mounted on said machine head adapted to guide said tape from said pulley to said foot, and a lever mounted on said foot and having an eye, adapted to feed the tape be- 30 tween the folds of the seam whilst this is being formed.

2. A device on a folding machine, comprising in combination with the machine table and machine head and the folding foot, a stand on said table, 35 a carrier on said stand, a roll adjustably mounted in height on said carrier and adapted to receive a supply of reinforcing tape, a paste container below said table adapted to coat with paste the tape running from said carrier, a pulley adjusta- 40 bly mounted in height on said stand adapted to guide the pasted tape leaving said container, a guide bar mounted on said machine head adapted to guide said tape from said pulley to said foot, and a lever mounted on said foot and having an eye, 45 adapted to feed the tape between the folds of the seam whilst this is being formed.

ADOLF STAMPFLI.
